UNITED STATES PATENT OFFICE

2,165,893

ALARM

Harry A. Gunion, Frankfort, Ind.

Application December 10, 1936, Serial No. 115,227

2 Claims. (Cl. 200—106)

This invention relates to burglar and similar alarms and particularly to an alarm device employing a normally open circuit which extends into a protected area, whereby the alarm will be operated when the circuit is completed by an unwarranted or undesired action in that area.

A primary object of the invention is to provide an alarm device of simple and compact construction which will give a continuing visible and audible signal once the portion of the circuit in the protected area has been completed, even though that circuit be immediately broken again.

Another object of the invention is to provide an alarm device which will operate on an ordinary alternating current source, thereby doing away with batteries or transformers usually employed with such devices.

Other objects and advantages of the invention will become apparent from the following detailed description and the accompanying drawing, in which:

Fig. 1 is a side elevation, partly in section, of an embodiment of the invention;

Fig. 2 is a sectional view taken on line 2—2 of Fig. 1;

Fig. 3 is an end elevation, partly in section;

Fig. 4 is a diagrammatic view illustrating the circuits employed and with the operating coil and related mechanism shown in perspective; and

Fig. 5 is a fragmentary perspective view of the insulated pivot support for the holding switch member.

The alarm device is housed in a casing 10 mounted on a base 11 which is preferably made of insulating material. An L-shaped strip of insulating material 12 is mounted on the base 11, with its shorter end 12' turned upwardly to form an upstanding panel upon which is mounted a pair of spaced contact elements 13 and 14. The bracket plate 15 of the trip mechanism overlies the strip 12 and a single set of bolts 16 serves to secure these parts to the base 11. The frame 17 of a relay or trip coil 18 is secured, by welding or the like, to the bracket plate 15, and one end of the plate 15 is formed with spaced ears 19 between which a holding switch member 20 is pivotally mounted for engagement with the contacts 13 and 14 at one extremity of its pivotal movement.

As best shown in Fig. 5, the lower end of the member 20 is rolled over to form a sleeve for receiving the tube 19a of insulating material, and insulating bushings 19b are placed on the end 55 of the tube to space the edges of member 20 from

the ears 19. A pivot pin 19c extends through the ears 19 and tube 19a to complete the insulated pivotal support for member 20.

The frame 17 has upturned arms 21 and 22 between which the coil 18 and its core 18' are seated, and the armature 23 extends over and is pivotally mounted on the end of arm 21. Lateral movement of the flat plate armature is prevented by ears 24 on the arm 21 that project through notches 25 in the edges of the armature. A relatively stiff spring 26, between the projecting end 27 of the armature 23 and a prong 28 struck out from the arm 21, tends to hold the armature in raised position against a stop 29 that may be a central extension of the arm 21, which extension passes through an opening 30 in the armature 23 and is bent to overlie the armature.

The other arm 22 of the frame 17 carries an upstanding metal plate 31 which is insulated from the arm by a block of insulating material 32. A coil spring 33 is mounted between the metal plate 31 and the free end of the latch member 20 and tends to force said member into engagement with the contacts 13 and 14.

The switch member 20 is normally latched in "off" position, Figs. 2 and 3, by the integral hook portion 34 which engages in an opening 35 in the armature 23. A push button 36 is loosely mounted in the panel for swinging the switch member into this open-circuit position, the push button being aligned with an opening 37 in the casing 10 for operation by a small rod, such as a pencil.

An electric lamp 38 is mounted in a socket 39 on the base 11, and a colored lens 40 is mounted in the front wall of the casing 10 to give a visual signal when the alarm is energized.

The parts so far described form a unit that may be connected between a source 41 of alternating current, such as the usual 110 volt, 60 cycle alternating current line, and a protective circuit that extends to the area to be guarded. A switch 42 is included in the connections, being shown diagrammatically in Fig. 4 as a single pole, single throw switch, but the switch may be merely a separable plug connector for insertion in a wall socket to connect the alarm system to the power line.

The lamp 38 and trip coil 18 are serially connected between the lead 43 and plate 31 by the coil terminals 44, 45, respectively. One wire 46 of the protective circuit extends from the plate 31 to a normally open switch 47 at the area to be protected, and the return wire 48 is connected to the contact 13 on the insulated strip 12. 55

The series circuit of these parts is completed to the power source by the lead 49 that extends from contact 13 to the switch 41.

It will be noted that the spring 33 forms an electrical connection between plate 31 and the switch plate 20, and that the plate 20 and contact 13 thus form a holding switch in shunt with the switch 47 of the protective circuit.

An alarm-controlled circuit may be located in 10 the protected area, as indicated by wire 50 that extends from the terminal 14 to load devices 51 in the protected area, the return wire 52 from such devices being connected to the power source lead 43. The nature of the switch 47 and the 15 devices 51 will depend upon the purpose of the protective system.

The illustrated embodiment, including the Fig. 4 circuit, is particularly useful as a burglar alarm for barns, poultry houses and similar buildings. 20 The normally open switch 47 may be of any known type having means, not shown, for connection to or across doors or windows for closing the switch when the door or window is opened. When used as a burglar alarm, the load 25 devices 51 will be lights positioned to illuminate the exterior of the building. When used as a fire alarm, the switch 47 will be of a known thermal type and the load devices 50 may be the electrically actuated valves of a sprinkler system. 30 The apparatus is placed in operation by latching the switch plate 20 to the armature 23, and closing switch 42. A closure of the switch 47 will then complete the described series circuit to energize the trip coil 18. The armature 23 is attracted to the coil, thus releasing the plate 20 which engages the contact 13 to complete a holding circuit around the switch 47. The circuit thus remains energized until the button 36 is 35 pressed inwardly to latch the switch plate 20 to the armature 23.

Due to the alternating current employed and the choice of a relatively stiff spring 26, the armature 23 will vibrate continuously between the stop 29 and the core 18, thus acting as a buzzer 45 to give a continuing audible signal in addition to the visual signal afforded by the lamp. This action is preferable to the usual make-and-break types of buzzer circuits for a number of reasons. In the first place, the alarm is very reliable over 50 long periods as the operation does not depend upon the particular adjustment of vibratory contacts. Further, the initial cost is decreased by the omission of vibratory contacts and this, as 55 well as the "fool-proof" nature of the alarm makes it particularly useful in the protection of outbuildings. The relatively low sound produced by the armature under the joint action of the stiff spring and the alternating magnetic field is sufficient to awaken the property owner but will 60 not be heard at the protected area, thus giving the property owner the advantage over the thief, particularly when the auxiliary lighting circuit 50-52 is not used.

The visual signal afforded by the lamp 38 is of 65 advantage in some instances, but the primary function of the lamp is that of a resistor which limits the voltage drop across the relay coil. The lamp may, for example, be of the 15 watt, 110 volt type, which has a resistance of about 810 70 ohms. The coil 18 may consist of about 2200 turns of No. 34 wire (0.007 inch diameter), enamel or cotton covered, having a resistance of about

120 ohms. The voltage drop across the coil will therefore be about 15 volts.

While a preferred embodiment of the invention has been shown and described, it will be understood that various modifications and changes 5 in the details of construction may be resorted to without departing from the spirit of the invention within the scope of the appended claims.

I claim:

1. A circuit control device for an alarm system 10 comprising a base member, a coil frame mounted on said base, a trip coil mounted in said frame, an armature pivotally mounted on said frame across the end of said coil, a relatively stiff spring tending to move said armature from said coil whereby said armature will be attracted to said coil and will vibrate continuously when said coil is traversed by alternating current, an upstanding panel carried on said base adjacent said coil frame, a contact carried by said panel, an upstanding switch plate pivotally mounted between said frame and said panel, a spring normally biasing said switch plate into engagement with said contact, cooperating latch means on said armature and said switch plate operative to latch said switch plate in a position out of engagement with said contact when said armature is away from said coil and said switch plate is tilted out of engagement with said contact, manually operated means for moving said switch plate to 30 latching position against the action of said spring, and an electrical connection between said switch plate and one terminal of said coil; whereby an alarm circuit may be completed by connecting a current source between the panel contact and the second coil terminal, and connecting an alarm switch between the first coil terminal and the panel contact, said switch plate engaging the panel contact on initial energization of the coil to complete a holding circuit. 35

2. A circuit control device for an alarm system comprising a base member, a U-shaped coil frame mounted on said base, a trip coil mounted in said frame, an armature pivotally mounted on one leg of said frame and extending across 40 the end of said coil, a relatively stiff spring tending to move said armature from said coil whereby said armature will be attracted to said coil and will vibrate continuously when said coil is traversed by alternating current, an upstanding panel mounted on said base in spaced relation to the other leg of said coil frame, a contact carried by said panel, an upstanding switch plate pivotally mounted between said frame and said panel having an upper end overlying said armature, a spring between said frame and switch plate normally biasing the latter into engagement with said contact, said spring being insulated from said frame, manually operated means for tilting said switch plate out of engagement with 45 said contact toward said frame, cooperating latch means on the upper end of said switch plate and said armature operative to latch said switch plate in said last mentioned position when said armature is away from said coil, and an electrical connection including said spring between said switch plate and one terminal of said coil, said panel contact and the second coil terminal being adapted for connection across a source of alternating current whereby an alarm switch may be 50 connected between the panel contact and the first coil terminal. 55

HARRY A. GUNION.
